JOHANN JACOB KNECHT, OF KAPPEL, NEAR CHEMNITZ, GERMANY, ASSIGNOR TO
THE FIRM OF MASCHINENFABRIK KAPPEL A. G., OF KAPPEL, NEAR CHEMNITZ, GERMANY.

EMBROIDERING-MACHINE.

1,120,722.

Specification of Letters Patent.

Patented Dec. 15, 1914.

Application filed October 20, 1913. Serial No. 796,305.

To all whom it may concern:

Be it known that I, JOHANN JACOB KNECHT, a citizen of the Confederation of Switzerland, and resident of Kappel, near 5 Chemnitz, in the Kingdom of Saxony, Germany, have invented certain new and useful Improvements in Embroidering-Machines, of which the following is a specification.

This invention relates to certain improvements in embroidering machines and more particularly to mechanism for counterbalancing the weight of the tambour frame of the type in which the tambour frame is supported by a parallel motion mechanism, 15 comprising a plurality of connected pivoted elbow levers provided with compensating spring mechanism for counterbalancing the weight of the frame.

The present invention relates to that class 20 of compensating mechanism in which not only the varying forces of the counterbalancing springs, as they are expanded or contracted during the movements of the tambour frame, are automatically compensated, but in which the varying load moment due to the varying leverage of the 25 weight of the tambour frame about the pivots of the supporting elbow levers is also automatically compensated by means of a 30 rocking member having a correspondingly curved surface and a flexible member having rolling contact with the curved surface.

According to the present invention the 35 rocking member is constructed in the form of a cam which rotates in unison with a cylindrical member, the cam being connected to the counterbalancing spring by a flexible member which makes rolling contact with the cam, while the cylindrical member is 40 connected to one arm of one of the elbow levers constituting the parallel motion mechanism by a second flexible member which makes rolling contact with the cylindrical member.

45 In order that the invention may be more clearly understood reference is made to the accompanying drawing illustrating the preferred construction of my improved counterbalancing mechanism in elevation as applied 50 to the tambour frame of an embroidering machine.

In the drawing 1 indicates the usual movable tambour frame of an embroidering machine which rests on the system of levers, 55 two of which are shown on the drawing,

these levers constituting the usual parallel motion mechanism. Pivotedly mounted at 3 on brackets 2 are elbow levers 4, 4^a, the arms 4 carrying rollers 5 which support the tambour frame, while the arms 4^a are connected 60 by means of a wire 6. Secured at one end to a stationary support 7 is a counterbalancing spring 8, the free end of which is connected to a flexible metal band 9 which makes rolling contact with the curved surface 65 of a rocking member or cam 10 rotatably mounted on a shaft 11 carried in suitable bearings 12. The flexible member passes around the curved surface of the cam 10 and is secured thereto at 13. It will thus 70 be seen that the tendency of the spring 8 is to rotate the cam 10 in anti-clockwise direction. Rotating in unison with the cam 10 is a cylindrical member or roller 14 likewise mounted on the shaft 11, and connected 75 to the cylindrical member at the point 15 is a flexible metal band 16 connected to an adjusting element 17 adjustably mounted in the end of the arm 4^a of one of the elbow levers. The weight of the tambour frame 1 80 will thus tend to rotate the cylindrical member 14 and cam 10 in clockwise direction, this tendency being equalized by the retracting force of the spring 8 so that the tambour frame 1 is supported by the action of the 85 spring 8.

If the tambour frame is moved upwardly or downwardly from the position shown on the drawing during the usual operations of the embroidering machine, the arms 4 of the 90 elbow levers will follow the movement of the tambour frame and the cam 10 will be correspondingly rotated, while the leverage of the spring 8 about the shaft 11 will vary according to the position of the cam 10, thus 95 compensating for the variations in the retracting force of the spring 8.

Since the leverage of the weight of the tambour frame 1 about the axis 3 of the elbow levers varies according to the position 100 of the tambour frame, it is necessary to construct the curved surface of the cam 10 in such a manner as to also compensate for this variation. For this purpose the required curvature of the cam may be determined 105 either mathematically or empirically.

I claim:—

1. In an embroidering machine having a movable tambour frame, a counterbalancing mechanism therefor comprising a plurality 110

2
of elbow levers, one arm of each lever supporting said frame and the other arms of said levers being connected together, a rotatable cylindrical member, a flexible member 5 connecting one of the connected arms of said levers to said cylindrical member and adapted to make rolling contact with the latter, a rocking member rotating in unison with said cylindrical member and having a 10 curved surface, a counterbalancing spring fixed at one end and a flexible member connecting the free end of said spring with said rocking member and adapted to make rolling contact with the curved surface 15 thereof, the form of said curved surface being such that both the varying load moment of the frame and the varying forces of the spring are compensated.

2. In an embroidering machine having a 20 movable tambour frame, a counterbalancing mechanism therefor comprising a plurality of elbow levers, one arm of each lever supporting said tambour frame and the other arms of said levers being connected together, 25 a rotatable roller, a flexible band connected at one end to and passed around said roller and connected at its other end to one arm of the connected arms of said levers, a rocking member rotating in unison with said roller 30 and having a curved surface, a counterbalancing spring fixed at one end and a flexible member connecting the free end of said spring with said rocking member and

adapted to make rolling contact with the curved surface thereof, the form of said 35 curved surface being such that both the varying load moment of the frame and the varying forces of the spring are compensated.

3. In an embroidering machine having a 40 movable tambour frame, a counterbalancing mechanism therefor comprising a plurality of elbow levers, one arm of each lever supporting said frame and the other arms of said levers being connected together, a rotatable cylindrical member, a flexible member 45 connecting one of the connected arms of said levers to said cylindrical member and adapted to make rolling contact with the latter, a curved cam rotating in unison with 50 said cylindrical member, a counterbalancing spring fixed at one end and a flexible band connected at one end to the free end of said spring and passed at its other end around 55 said curved cam and secured thereto, the form of said curved surface being such that both the varying load moment of the frame and the varying forces of the spring are compensated.

In testimony whereof I have affixed my 60 signature in presence of two witnesses.

JOHANN JACOB KNECHT.
